UNITED STATES PATENT OFFICE

EADS JOHNSON, OF MORRISTOWN, NEW JERSEY

DESIGN FOR A MARINE TRACTOR

Application filed April 23, 1932. Serial No. 43,588. Term of patent 8½ years.

To all whom it may concern:

Be it known that I, EADS JOHNSON, a citizen of the United States, residing at Morristown, in the county of Morris and State of New Jersey, have invented a new, original, and ornamental Design for Marine Tractors, of which the following is a specification, reference being had to the accompanying drawing forming part thereof.

In the drawing, Fig. 1 is a side elevation of a marine tractor showing my new design.

Fig. 2 is an end elevation of the same.

I claim:

The ornamental design for a marine tractor as shown.

EADS JOHNSON.
